UNITED STATES PATENT OFFICE.

JOSEPH P. BUCKINGHAM, OF NEW YORK, N.Y.

BOX.

SPECIFICATION forming part of Letters Patent No. 325,729, dated September 8, 1885.

Application filed December 3, 1884. (No model.)

To all whom it may concern:

Be it known that I, JOSEPH P. BUCKINGHAM, a citizen of the United States, residing in the city, county, and State of New York, have invented certain new and useful Improvements in Boxes, of which the following is a specification.

My invention relates to paper tubes or boxes, and more particularly to that class which are adapted to be folded flat for transportation and storage, and opened to receive and hold the contents; and it has for its object to improve the construction of such tubes and cases, and to render them stronger and more durable without materially increasing their cost; and to these ends my invention consists, primarily, in a folding re-enforced tube constructed as more particularly hereinafter specified, and, secondly, in such a tube having closing end pieces.

Referring to the accompanying drawings, forming part of this specification, Figure 1 is a perspective view of my improved tube. Fig. 2 is an end view of the tube folded flat. Fig. 3 is a cross-section of the tube. Fig. 4 is a cross-section of a modified form of tube. Fig. 5 is a perspective of the tube, showing one form of end-closing pieces. Fig. 6 is a perspective showing the end closed.

It is desirable in constructing tubes or cases of the class mentioned to have them sufficiently strong to resist any ordinary pressure or blow without breaking or giving way so as to allow the contents thereof to be injured, and this has necessitated the use of comparatively heavy paper or board; and as it is also desirable to have the outside of the tube present a finished appearance and be smooth for the reception of a label or printed matter, it has been necessary to use a good quality of stock, which is expensive, or to construct the tube of a poorer quality of stock and cover it with a thin, fine quality of material. Both of these modes of construction have their advantages and disadvantages, and it is the object of my invention to produce a tube that shall embody the former and avoid the latter, and at the same time be inexpensive to manufacture. I take a rectangular piece of stock, which may be Manila paper, card-board, or similar material which has a smooth outer surface, and form it into a tube, A, of any shape, a square one being

shown in the drawings, and re-enforce the sides of the tubes with strips B, of heavier and cheaper material, by securing the strips to said sides by paste or glue, leaving a space, C, between the edges of the strips for the folding-lines of the tube, so that it can be readily folded, as shown in Fig. 2, for transportation or storage. With some classes of material the overlapping pieces forming the bottom D, Fig. 4, for instance, may be made substantially of the same size as the top, and by securing them together they will form a sufficiently rigid portion of the tube; but when the outer material is too light for such construction, or of a finer quality, the overlapping flap or edge d is made short and is secured to the bottom flap, and a re-enforcing piece, D', is applied, as in the sides and top of the tube, as shown in Fig. 3. It will thus be seen that I am able to produce a tube that is exceedingly strong and rigid when extended, and can be readily folded and packed, while it is comparatively inexpensive, as there is no waste of material, the several portions being rectangular in shape; and while the outside of the tube is made of good stock, the strengthening-pieces are of a cheap grade, and small pieces of that even may be utilized. It is obvious that such a tube may be used for many purposes alone, or in combination with slides or drawers, and that the re-enforced sides will maintain their shape against a considerable pressure; but sometimes it is desirable to close the ends of the tube—as, for instance, in corset-boxes and the like—and in Fig. 5 I have shown a means for closing the ends which is simple and effective. An end piece, E, having projections or ends e e' made of the same material as the outside of the box and re-enforced by pieces of cheaper material, b' b'', has one of the ends, as e, secured between the bottom side, D, of the box and the re-enforce pieces D', and the other end, e', is adapted to tuck into the end of the tube, the edges f f fitting into recesses or slots made by cutting away a portion of the side re-enforcing pieces, as shown at dotted lines g g.

In order to relieve the pressure of the contents of the box upon the end piece and to prevent the same from being forced out, the outer portion of the box A has projecting flaps F F on its sides not re-enforced, which are folded inwardly before the tucking-flap is

fixed in its closing position, and are covered by the end portion, E, when the box is closed. This end-closing piece does not in any way interfere with the folding of the tube when it is out, and at the same time assists materially in sustaining the tube in its upright position when closed.

It is understood that other forms and constructions of closing-pieces can be used with my improved tube without affecting that part of my invention.

What I claim is—

1. A folding re-enforced paper tube consisting of an outer piece of material joined at its edges to form a tube, and strips of re-enforcing material secured to each of the inner sides, leaving spaces between their contiguous edges of a width sufficient to form the edge

folds and to permit the tube to be folded flat, substantially as described.

2. The combination, with a re-enforced tube consisting of an outer piece of material having re-enforcing strips secured to the sides, and having the flaps F extending beyond the reinforced portions, of end pieces, E, having projections, one of which is secured between the outer and the re-enforcing piece, and the other being adapted to tuck into the tube, substantially as described.

In testimony whereof I have signed my name to this specification in the presence of two subscribing witnesses.

JOSEPH P. BUCKINGHAM.
